UNITED STATES PATENT OFFICE.

WILLIAM J. JOHNSON, OF ALLENDALE, ENGLAND.

IMPROVEMENT IN APPARATUS FOR CONDENSING AND PURIFYING THE SMOKE OF METALLURGIC FURNACES.

Specification forming part of Letters Patent No. **136,066**, dated February 18, 1873.

To all whom it may concern:

Be it known that I, WILLIAM JAMES JOHNSON, of Allendale, in the county of Northumberland; Kingdom of Great Britain and Ireland, have invented an Improved Method of and Apparatus for Condensing and Purifying Smoke and Vapors, of which the following is a specification:

This invention is designed to effect the condensation and purification of smoke, vapors, fumes, and gases evolved from furnaces, hearths, or other places where combustion is carried on; the object of the said invention being to condense or extract the soot or unconsumed carbon and any metallic, sulphurous, deleterious, and other particles that may be contained therein, and to allow the purified vapor only to escape into the atmosphere; and the apparatus to be employed for this purpose consists, principally, of a revolving wheel or drum, with projections dipping into water or other liquid for the purpose of producing a shower or spray, in combination with an inclined screen constructed, as hereafter explained, of a number of partitions provided with horizontal ribs, between which the smoke, fumes, or vapor is caused to pass under the influence of the shower or spray. In any convenient part of the flue, between the furnace or hearth and the chimney or outlet, I form a chamber, the bottom part of which serves as a tank to contain water or other liquid. Above the surface of such water or liquid is mounted a revolving wheel or drum, having projections or wings on the periphery, which dip into the water and, as the wheel or drum revolves, throw up a shower or spray in an inclined direction. In advance of this wheel, and near to the chimney, I form a net-work or an inclined screen, constructed of a number of vertical partitions of graduated heights, those nearest to the wheel being the lowest, so that the top of the partition forms an incline at about the same angle that the shower or spray is thrown off from the wheel or drum. These partitions are provided with laths, ribs, or gratings, set horizontally or at an inclination, and the whole screen is so arranged and situated that the smoke, fumes, or vapor passing from the furnace or hearth to the chimney or outlet must necessarily pass through the spaces between these said partitions, while the shower of wa-

ter is projected over the top of the same and falls down in a minutely-divided state from one lath, rib, or grating to the other between the partitions. By these means all soot or carbon in a solid state is washed out of the smoke, and also all acids or soluble or insoluble metallic, sulphurous, or other particles are removed therefrom. In fact, the smoke, fume, or vapor becomes thoroughly washed and purified on its passage through the shower or spray and between the partitions, and only the purified vapor escapes by the chimney or otherwise to the atmosphere. The water from the partitions falls again into the tank, and is used over and over again. The soot or carbon, and also the other matters extracted from the smoke or vapor, whether solid or in the form of a solution, may be extracted from the wash-water and utilized in a variety of ways, according to the nature of the material under combustion.

Instead of a drum or wheel, as above described, any other means of producing a shower or spray by water under pressure, or by the condensation of steam, might be employed in combination with the screen; and by putting vanes on the wheel and admitting the smoke, fume, or vapor at the center, the draft may be greatly accelerated. In some instances, also, I propose to place a jet of steam in the chimney for the same purpose.

In order to enable others skilled in the art to make and use my invention, I will now proceed to describe its construction and operation.

On reference to the accompanying drawing, which forms part of this specification, Figure 1 is a longitudinal section, taken vertically through the apparatus. Fig. 2 is a similar section, taken horizontally; and Fig. 3 is a transverse section through about the line A B.

a a is part of the flue leading from the furnace, hearth, or other place where the combustion is carried on; and *b b* is the lower part of the chimney. *c c* is the purifying-chamber, the bottom part of which forms a tank, *d d*, for containing the water or other liquid employed.

It will be observed, on referring to Figs. 2 and 3, that the lowest part of this tank is carried outside the flue, and is open at the top, so as to allow of access to remove the solid or other matters extracted from the smoke or fumes,

which may be utilized in a variety of manners, according to the nature of the material under combustion. The escape of smoke or gases at this point is prevented by placing the openings *e e* (communicating with the interior) below the level of the water or other liquid. *f f* is the wheel for throwing up the spray or shower of water or other liquid, as seen at Fig. 1. It is mounted on a shaft, *g g*, which passes through the wall of the flue, and is driven at the requisite speed by means of a band-pulley or toothed wheel in connection with the steam-engine or other motive power. This wheel is shown in the drawing with tines or pegs dipping into the water or other liquid; but, as previously mentioned, it may be made in the form of a fan, so as to increase the draft, in which case the flue would be carried outside the ends, and the smoke or fumes be drawn in round the axle; or other means for throwing up a spray or shower in the manner indicated at Fig. 1 might be employed. The inclined screen or grating is shown at Figs. 1 and 2, and consists of a number of vertical partitions, *h h*, of graduated heights, the partition next to the wheel being the lowest, and dipping into the water or other liquid so as to prevent any smoke or fumes from passing to the chimney excepting through the screen. On each side of each partition there are fixed, either horizontally or at an inclination, several laths or ribs, *i i*, of an angular or other suitable section, the whole forming a screen, in passing

through which the smoke or fumes become thoroughly washed and purified, as previously described. The arrows in Fig. 1 show the course of the smoke or fumes.

I may here remark that, although only one wheel and one screen are shown in the drawing, it will be evident that two or more wheels and screens may be placed in one flue, if found desirable.

k k represent a jet of steam, which may be placed at the foot of the chimney, if further aid to the draft should be required.

I am aware that the products of combustion from a furnace have been passed through a chamber into which water is thrown in the form of spray by a rotating wheel, and I make no claim to this; but

I claim—

1. The combination, with a flue for the passage of the products of combustion, of a series of slats or a screen, or its equivalent, from which water is caused to fall in a constant shower, substantially as described.

2. The combination, with the slats or screen, of a wheel, by which water is thrown upon the slats, as specified.

In testimony whereof I have signed my name to this specification in the presence of two subscribing witnesses.

W. J. JOHNSON.
